WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,260,616.

Specification of Letters Patent.

Patented Mar. 26, 1918.

Application filed March 6, 1912. Serial No. 681,965.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

10 This invention relates to carry-over mechanism, and is herein disclosed as applied to a computing head of the master wheel type in which the master wheel operates *serialim* on the periphery of a series of computing wheels, or wheels driving said computing wheels.

It has heretofore been found frequently necessary to employ strong detents for alining the computing wheels with one another, 20 or to have a carry-over mechanism in which parts are reciprocated into and out of engagement with the computing wheels, or to gear together various parts of the mechanism with a multitude of small, loose, separate parts which are difficult to assemble, 25 awkward to adjust, and liable to disarrangement. In other machines elaborate connections have been provided for disconnecting the computing wheels that are lower in denomination than that which is in engagement with the master-wheel. These features make such machines hard in operation and difficult to repair. The present invention is intended to provide improved means for 30 avoiding such difficulties and such complex mechanism; and it is herein disclosed substantially as in the nature of an improvement on co-pending application No. 642,183, filed August 3, 1911.

40 In said application the computing wheels as disclosed each comprise two concentric toothed members, of which one member always remains in engagement with a carry-over mechanism, while the other or principal member is arranged to be engaged by a master-wheel; and the member engaged by the carry-over mechanism is always either positively driven or positively locked through said mechanism by the computing 45 wheel next lower in denomination. This is accomplished by means of a Geneva lock, without reliance upon springs. A coupling device causes these two members of each computing wheel to revolve as a unit, and 50 this coupling device is placed inside the

computing wheel. The carry-over mechanism is therein shown outside the computing wheels, and the coupling devices are so related to the plane of the master-wheel, that each computing wheel higher in denomination than the one momentarily engaged by the master wheel is controlled by one of said coupling devices, while the computing wheels lower in denomination have no such coupling device and consequently their principal members cannot be affected by the carry-over mechanism.

60 In the present invention the master-wheel is preferably located outside the computing wheels, and dial wheels are preferably provided separately from the computing wheels; and preferably both the dial wheels and the computing wheels are geared together by means of an intermediate gear on which the master wheel operates. By having the main part of the computing mechanism separate from the dial wheels, a broad surface is obtained on those wheels, on which distinct numerals may be placed. Preferably positive means are provided for locking 65 all computing wheels not engaged by the couplers or master-wheel, and also preferably positive alining means for the couplers are arranged to keep them in such position that their teeth will mesh with the teeth of 70 the computing wheels, as they slide into each other. The present invention provides a construction economical to build, easy to repair, and easy to drive.

75 Other features and advantages will hereinafter appear.

In the accompanying drawings,

Figure 1 represents a section through a totalizer.

Fig. 2 is a front view of the same, partly broken away.

Fig. 3 is a perspective view of a dial wheel and certain associated parts.

Fig. 4 is a section of the broken line A—B—C—D of Fig. 1.

Fig. 5 is a diagrammatic plan view of Fig. 4.

Fig. 6 shows a computing wheel and its associated carry-over wheel viewed oppositely to Fig. 1.

Fig. 7 is a perspective view of a coupler.

The invention is herein disclosed as applied to a typewriting machine and in the drawings, 1 is the front of a typewriting machine in grooves 2 in which ride arms 3

of a totalizer carriage 3^a, carrying a totalizer 4. In said totalizer are mounted dial wheels 5 driven by a master-wheel 6 through an intermediate wheel 7, there being a separate intermediate wheel 7 for each dial wheel and one master-wheel for the totalizer. Each of said intermediate wheels 7 also drives a computing wheel 8 which is formed with internal teeth 9 and external 10 teeth 10.

Against the face of said computing wheel toward the next lower computing wheel in 15 denomination (which face is the part carrying said teeth 10) is a loose wheel 11 having external teeth 12 and internal teeth 13; both sets of said teeth preferably corresponding to the teeth on the computing wheel proper.

The peripheral teeth 10 on the computing 20 wheel mesh with the teeth 14 on the intermediate wheel so that said computing wheel is driven by the master-wheel when said master-wheel is in mesh with said intermediate wheel.

25 A carry-over wheel 18 is arranged outside of each computing wheel and has teeth 19 meshing with the teeth 12 on said loose wheel. On the periphery of the adjoining computing wheel next lower in denomination 30 is cut a ledge 20 in the groove formed by which, ride narrow teeth 21 on said carry-over wheel. Said teeth 21 are adapted to be struck by teeth 22 on said adjoining computing wheel once in each revolution of 35 said computing wheel, and a broad tooth 23 on said carry-over wheel is arranged to sink into a broad space 24 on said adjoining computing wheel when it is turned by teeth 21 striking teeth 22. Said broad teeth 23 40 normally ride on the periphery of said adjoining computing wheel forming a Geneva lock with it for the carry-over wheel, as seen in Fig. 3.

Thus it will be seen that the Geneva lock 45 formed by the carry-over wheel and the computing wheel will be broken once in each revolution, due to one of the teeth 21 on said carry-over wheel being struck by a tooth 22 on the computing wheel, and the 50 carry-over wheel will turn until the next broad tooth 23 locks with the periphery of said computing wheel.

All computing wheels higher in denomination than the computing wheel engaging 55 the master-wheel have internal couplers 15 riding in them. Said couplers ride loose on a shaft 16, and teeth 17 on said couplers project between the internal teeth of the computing wheel and couple each computing 60 wheel with the loose wheel next below it in denomination so that said loose wheel and computing wheel will revolve as a unit when said coupler lies within them, forming what might be termed a composite computing 65 wheel.

Thus the extreme left-hand computing wheel in Figs. 4 and 5, and all wheels to the left of said wheel would therefore be engaged by couplers 15. The position of the master-wheel 6 is shown in dotted lines 70 in Fig. 5, and sleeve 16^a on shaft 16, holds the couplers so that the end one is always one computing wheel above the master-wheel. There are a sufficient number of couplers, so that when the master-wheel is 75 engaged with the units wheel of the totalizer, there will be one coupling for every computing wheel higher in denomination, and as the totalizer travels across the master-wheel, it will successively engage the 80 different couplers. No couplers are engaged with the computing wheels lower in denomination than the master-wheel. It will accordingly be seen that the carry-over wheels 85 for said computing wheels lower in denomination are connected only with the loose wheels, and so cannot operate on the principal members of the computing wheels.

The couplers to the left of the totalizer 90 are kept aligned by a bar 25 fast on the totalizer, and traveling with it, so that the teeth on the couplers will mesh with teeth on the computing wheels as they slide on to each other.

The computing wheels to the right of the 95 master-wheel are kept from turning by a blade or bar 26, which is fixed relatively to the plane of the master wheel, and extends between the internal teeth of the computing wheels. In this way, every dial wheel is kept 100 locked at all times through its computing wheel, unless the computing wheel is engaged and locked by its carry-over gearing or master wheel. The computing mechanism is therefore positively locked or positively driven.

Variations may be resorted to within the scope of the invention, and portions of the improvements may be used without others.

Having thus described my invention, I 110 claim:

1. In a computing machine, the combination with a plurality of computing wheels, of a driving gear co-axial with each wheel, a normally idle gear also co-axial with 115 said computing wheel, carrying mechanism, means including gear teeth for coupling a computing wheel of lower order and an idle gear of higher order during a carrying operation, and means co-operative with said 120 driving gear for actuating the same.

2. In a combined typewriting and computing machine, the combination with a traveling carriage, of a totalizer and a master wheel relatively movable under control of 125 said carriage, said totalizer comprising a plurality of dial wheels having numerals on the face thereof, a shaft for said dial wheels, a plurality of computing wheels, one for each dial wheel, a shaft whereon said com- 130

- puting wheels are mounted, carrying mechanism, a driving gear co-axial with each computing wheel, a normally idle gear also co-axial with each computing wheel, and 5 means for coupling a computing wheel of lower order and an idle gear of next higher order during a carrying operation, said master wheel coöperative with a driving gear and a dial wheel of the same denomination.
- 10 3. In a combined typewriting and computing machine, the combination with a traveling carriage, of a totalizer and a master wheel relatively movable under control of said carriage, said totalizer comprising a plurality of dial wheels having numerals on the face thereof, a shaft therefor, a plurality of computing wheels, one for each dial wheel, a shaft whereon said computing wheels are mounted, carrying teeth and a driving gear on each computing wheel, said driving gear being co-axial with its corresponding computing wheel, a normally idle gear also co-axial with said computing wheel, carry-over mechanism operated from said carrying teeth, and means for coupling a computing wheel of lower denomination and an idle gear of higher denomination during the carrying operation, said master wheel coöperative with a driving gear and a dial wheel of the same denomination.
- 15 4. A totalizer having denominational units, each unit comprising a computing wheel having a Geneva locking surface, carrying teeth and an external gear, said unit further comprising a loose wheel co-axial with said computing wheel, devices for coupling together said computing wheel and said loose wheel, carry-over devices operated from the carrying teeth on a computing wheel of a lower order and acting through said loose wheel and coupling devices to move a computing wheel of next higher order, said loose wheel being locked 20 by said Geneva locking surface except during the carrying operation, and means coöperative with said external teeth on said computing wheel for driving the same.
- 25 5. A totalizer and a master wheel movable relatively thereto, said totalizer comprising a plurality of dial wheels and a shaft therefor, a plurality of computing wheels, one wheel for each dial wheel, a shaft whereon said computing wheels are mounted, carrying mechanism, a driving gear co-axial with each computing wheel, a normally idle gear also co-axial with each computing wheel and external thereof, means for coupling a computing wheel of 30 lower order and an idle gear of next higher order during a carrying operation, and a series of intermediate wheels, one for each computing wheel, coöperating with the driving gear thereof and also with a dial wheel of corresponding denomination; said master wheel coöperating with said intermediate wheels during relative movement of said master wheel and said totalizer.
- 35 6. In a computing machine, the combination, with a plurality of computing wheels, each having a gear, and a master wheel for driving said computing wheels *seriatim* through said gears; of a loose gear for each computing wheel disposed co-axially therewith, each computing wheel and its associated loose gear having corresponding sets of gear teeth; carry-over mechanism engageable with said loose gears to turn the same; and coupling means engaging the teeth on a computing wheel and its said associated loose gear, to cause them to rotate in unison during the carry-over.
- 40 7. In a computing machine, the combination, with a plurality of computing wheels, each having an external peripheral gear, and a master wheel for driving said computing wheels *seriatim* through said gears; of an externally-toothed loose gear for each computing wheel, each computing wheel and its associated loose gear having corresponding sets of gear teeth; carry-over mechanism engageable with the external teeth on said loose gears to turn the same; and coupling means engaging the teeth on a computing wheel and its said associated loose gear, to cause them to rotate in unison during the carry-over.
- 45 8. In a computing machine, the combination, with a plurality of computing wheels, each having an external peripheral gear, and a master wheel for driving said computing wheels *seriatim* through said gears, of an externally-toothed loose gear for each computing wheel, each computing wheel and its associated loose gear having corresponding sets of internal gear teeth; carry-over mechanism engageable with the external teeth on said loose gears to turn the same; and coupling means disposed internally of said computing wheels and their associated loose gears for engagement with the internal teeth thereof, to cause a computing wheel and its loose gear to rotate in unison during the carry-over.
- 50 9. The combination, with a pair of juxtaposed, externally-toothed computing wheels, and an interposed loose gear disposed co-axially therewith; of a pair of externally-toothed dial wheels, one for each computing wheel; a pair of intermediate gears, each meshing with the teeth on a computing wheel and on a dial wheel; a master wheel arranged to engage and drive said intermediate gears *seriatim*; a carry-over device controlled by one computing wheel, and arranged to engage and drive said loose gear; and means for coupling said loose gear and the other computing wheel to rotate in unison during the carry-over.
- 55 65 70 75 80 85 90 95 100 105 110 115 120 125 130

- 4
10. A totalizer having denominational units, each unit above the lowest order comprising a computing wheel, a wheel co-axial therewith and fixed thereto, and a loose wheel also co-axial with said computing wheel; coupling devices including gear teeth between the denominational units, carry-over devices between said units operative from a computing wheel of lower order, and acting through said loose wheel and said coupling devices to turn a computing wheel of next higher order, and means acting to drive a computing wheel through the medium of said fixed wheel.
15. 11. A totalizer having denominational units, each unit above the lowest order comprising a computing wheel having a Geneva locking surface, carrying teeth, internal teeth, and an external gear, said unit further comprising a normally loose wheel co-axial with said computing wheel, said loose wheel having internal teeth of the same formation as the internal teeth on said computing wheel, devices for coupling together said computing wheel and said loose wheel, carry-over devices operated from the carrying teeth on the computing wheel of lower order, and acting through said loose wheel
- 5 and coupling devices to move a computing wheel of next higher order, said loose wheel 30 being locked by said Geneva locking surface, except during the carrying operation, and means co-operative with the external gear of said computing wheel for driving the same.
- 10 35
12. In a totalizer, the combination of lower and higher order computing wheels, each having tens-carrying teeth, tens-carrying mechanism for transmitting movement from a lower computing wheel to the 40 next higher computing wheel, and including a member engageable by the teeth on the lower computing wheel, a transmitting wheel moving with said member, a loose wheel engaged by said transmitting wheel, 45 means for coupling said loose wheel and the next higher computing wheel, and a driving gear for said computing wheel of higher order situated between the plane of the carrying teeth of said higher order 50 wheel and said loose wheel.
